AXEL L. LARSEN, OF ST. PAUL, MINNESOTA

GAME DEVICE

Application filed April 23, 1930. Serial No. 446,547.

My invention relates to game devices in general and more particularly to a device in which circular discs are removably securable concentric of an indicator spindle and further embodying new and novel means for spinning the indicator. The main object is to provide a simple, inexpensive and interesting game device, the use and construction of which is such that persons of practically all ages can use it for recreational purposes, a memory testing device, and for playing certain games in simulation of games hitherto well known.

The construction and use of my game device are hereinafter fully set forth, reference being had to the accompanying drawings showing a preferred embodiment and a limited number of discs of certain design as used in the playing of games.

In the drawings,—

Fig. 1 is a top view of my game device with its spindle rotating means in position to start rotation and a game-disc mounted on the device, the said disc being partly broken out.

Fig. 2 is a front view of Fig. 1, showing the removable game-disc in diametrical section longitudinally of the device.

Figs. 3 and 4 are face views of game-discs with two kinds of game means printed thereon; namely, a number game in Fig. 3 and a geographic game in Fig. 4.

Referring to the drawings by reference numerals, 5 is a base of suitable material such as metal, heavy cardboard or wood and shown as being of quadrangular formation, though the latter is not important.

On said base, near its outer edge is fixed as with rivets 6 (or screws) the lower horizontal arm 7A of a bar-metal frame, said frame comprising further an integral upright part 7B and an upper horizontal arm 7C extending integrally from the upper end of part 7B and said arm 7C being of course in spaced parallel position, rigidly over the board 5. Near the free end of arm 7C it is formed with an upward offset 7D, the length of which is preferably the same as the width of the bar and thus adapted to be frictionally engaged in a square-aperture 8A of a

circular game-disc 8 provided with the game-device. There may be a plurality of such discs provided with each device, in sets, the faces of said discs having circular arrangements of numbers, maps, questions, answers or various other representations all arranged for playing games as will presently be described.

9 is a vertical spindle with reduced ends of which the upper one is journaled in the frame offset part 7D and protrudes thereabove as a stub shaft 9A of polygonal form in cross section, and the lower reduced end of the spindle, 9B, is suitably journaled in the base 5 (see Fig. 2). 9D is a disc fixed on the central part of spindle 9. 10 is a pointed indicator resembling a clock-hand and its hub part provided with a polygonal bore 10B of a size permitting said indicator to be placed frictionally on the part 9A of the spindle or be readily removed therefrom.

11 is an elastic member preferably a common rubber band of suitable size and tied to post 7B of the frame as at 11A. From this fixed part of the band its main loop may be stretched past the disc 9D with one bight above and one below said disc, this stretching being done by simply engaging the band with a finger 12 as shown dotted in Fig. 1. When the extended rubber band is released by the finger, it immediately snaps toward post 7B and the closed end of the band engages the perimeter of disc 9B quite forcibly causing the said disc, spindle 9—9A and indicator hand 10 to be spun.

It will be readily understood that a game-disc 8 is first put in position concentric of the spindle 9, said disc resting on arm 7C of the frame and being also frictionally held by part 7D of the frame arm. Then the indicator hand 10 is placed on the spindle part 9A.

13 in Fig. 2 is a small spring arm pivoted or fixed on a pin 14 in the outer part of arm 7C of the frame, said spring arm extended toward the spindle, and serving as a friction catch to engage the perimetral part of a game-disc 8 under it.

As above stated the game-discs may be provided with printed or colored numbers,

figures, etc., on their faces in circular formation. The disc 8 in Fig. 1 is divided into a series of radial areas, each with a compound number, as 4—6, 1—6, etc., near the perimeter. Such compound numbers may represent any possible pair of numbers indicated on a pair of dice and therefore two or more players can use my game device to play a game with points reckoned as in playing a game of dice. The points for each play are determined by what position the hand 10 stops at, over the game disc.

In Fig. 3 a game disc face is shown having two circular rows of figures and providing for an interesting number game. For example, assuming that this disc is in use on the device, the hand 10 may stop at the dotted position indicated by letter A, to the right of No. 1 of inner row of figures. The player gets 11 points, adding the 10 of the outer circle to the 1 designated. But if the hand stops to the left of "1" as at B then the player gets 20 points, adding "1" to the "19" of the outer row of figures. An objective may be determined before starting the game and the player to first reach this objective wins the game.

Obviously, a large variety of games can be played. As another example Fig. 4 shows a game disc 8 with outline pictures of various states each numbered. A player must name the state pictured, where the hand 10 stops, then give further information about that state as called for in the center part of the disc. For such geographic game an information chart, pamphlet or the like may be provided so that players can check up to see if their answers are correct. Other games such as cards, fortune telling, stunts to be done by the players may also be provided for by furnishing a number of game-discs with each device, no two faces of each such set of discs having like games.

Mechanically, my device may be made to occupy very small space for shipping purposes. The frame can be disconnected from the base at 6, spindle 9 removed from operative position shown, and the actuated disc 9D may be removably fixed on spindle 9 (not shown). Thus all parts may be laid flat upon the base, including the game-discs, all in a shallow container.

I claim:

1. A game device of the class described, comprising a base, a frame fixed on said base and comprising two vertically spaced parallel arms and an upright post connecting said parallel arms integrally, a vertical spindle journaled in the upper frame arm and in the base and protruding above said arm, an actuating disc on said spindle, circular game-disc means adapted to be removably held on said upper frame arm concentric of said spindle; an elastic element fixed to said post and adapted to be

stretched in a horizontal line tangential of the actuating disc to contact with said disc when released, to cause rotation of the spindle by the contraction of the elastic element.

2. A game device of the class described, comprising a base, a frame fixed on said base and comprising two vertically spaced parallel arms and an upright post connecting said parallel arms integrally, a vertical spindle journaled in the upper frame arm and in the base and protruding above said arm, an actuating disc on said spindle, circular game-disc means adapted to be removably held on said upper frame arm concentric of said spindle, an elastic element fixed to said post and adapted to be stretched in a horizontal line tangential of the actuating disc to contact with said disc when released, to cause rotation of the spindle by the contraction of the elastic element, and an indicator hand removably fixed on said protruding spindle end and arranged to be rotated with the spindle in a plane parallel to and above a game-disc in operative position described.

In testimony whereof I affix my signature.
